FLAT KNITTING MACHINE

Max Nebel, Chemnitz, Germany

Application December 10, 1932, Serial No. 646,592
In Germany December 14, 1931

4 Claims. (Cl. 66—90)

My invention relates to flat knitting machines, and more particularly to a thread separator for such machines.

It is an object of my invention to improve a flat knitting machine of the kind described.

To this end, in combination with the usual jack and dividing sinkers, I provide a separator comb with a thread separator per dividing sinker, and an upwardly directed projection, or a pair of projections, at the free end of each separator for cooperation with the usual thread guides.

By these means, two or more threads are reliably separated during the sinking and placed into the corresponding throats of the jack and dividing sinkers. In this manner good work of various kinds is knitted, such as plated work, backed cloth, turn-over plated work, coloured patterned work and coloured patterned backed cloth; at the high velocity at which flat knitting machines are normally operated for knitting plain goods.

In the usual machines, the separation of the threads is influenced by accidental conditions, or by properties of the materials, or by the operating velocity.

This uncertainty is eliminated according to my invention by immediately and mechanically separating the threads and keeping them positively separated until the loops of a complete course have been sunk and the dividing sinkers advance for dividing them.

There is no variable lead for the thread guides but the thread guides move together and in unison with the usual lead of the guide for the ground thread.

In the drawings affixed to this specification and forming part thereof a flat knitting machine, various types of separators and sinkers embodying my invention and various knitting operations performed by them, are illustrated diagrammatically by way of example.

In the drawings

Fig. 1 is a transverse section of a flat knitting machine equipped with my separator.

Figs. 2 to 5 illustrate the separation of the plating and ground threads in a fabric having only these two threads, by means of a separator having a single upwardly directed projection at its free end.

Fig. 6 is an elevation of the front end of a jack sinker and

Fig. 7 is an elevation of the front end of a dividing sinker for the operation illustrated in Figs. 2 to 5.

Fig. 8 is a section on the line VIII—VIII in Fig. 3, with parts omitted,

Fig. 9 is a diagrammatic plan view showing the thread guides, the needles, the jack and dividing sinkers, and separators according to my invention.

Fig. 10 shows a stage in the knitting of work having a pattern or reinforcing thread in addition to the plating and ground threads,

Fig. 11 shows a stage in the knitting of work backed with loop plush,

Fig. 12 illustrates a stage in the knitting of backed cloth, with separators, having a pair of upwardly directed projections, or a fork at their free ends,

Fig. 13 illustrates a stage in the backing of plated work, also with forked separators,

Fig. 14 shows the front end of a jack sinker, and

Fig. 15 shows the front end of a dividing sinker for performing the operation illustrated in Fig. 13.

Referring now to the drawings, and first to Fig. 1, the frame of the flat knitting machine is built up from a pair of end plates 34, only the rear end plate being visible in Fig. 1, and transverse bracing members 35, 35a and 36.

37 is one of two or more bearings supported by the end plates 34 in which the supporting shaft 38 for the narrowing machine 41 is mounted to oscillate. 39 are arms on the shaft 38 and 40 is the narrowing shaft which is supported by the free ends of the arms 39. In the example illustrated, the arms 39 are connected to brackets 39a which in turn support the narrowing shaft. The narrowing machine 41 is secured to the shaft 38. 40. 42 are pitmen which are pivotally connected to the narrowing machine 41, or to its shaft 40, at their upper ends and to rocking levers 43 at their lower ends. 46 is a cam shaft, 45 are cams on the shaft and 44 is a roller on each rocking arm 43 which cooperates with a cam 45. It will be understood that as many arms 39, supports 42 and rocking levers 43 are provided as required for the structure of a machine of a given length.

47 is one of two or more brackets on the bearings 37 of the shaft 38, and 49 is one of two or more braces which are secured to a table 50 of the machine, for supporting together a shaft 48 which is mounted to oscillate in suitable bearings at the inner ends of the brackets 47 and the braces 49. 51 is one of two or more arms on the shaft 48 which together support a bar 17 in which separators 16 are mounted, as will be described. 53 is a lever which is keyed on the shaft 48, 54 is a roller near the lower end of the lever 53, 52 is 55

- a cam on the shaft 46 and 55 is a spring which is anchored to the transverse bracing member 36 at one end and to the free end of the lever 53 at its other end, for applying the roller 54 to the 5 cam 52. By a single lever 53, or by any number of levers and cams, as may be required by the length of the machine, the shaft 48 is oscillated and the arms 51, with the bar 17, are rocked about the axis of the shaft.
10. 1, 2, 3 and 4 are thread guides, 10 is an upper and 11 is a lower bar for the jack and dividing sinkers which cooperate with the thread guides, and 13 is the bar of the frame needles 12. 14 is a knock-over comb which is arranged below the 15 lower sinker bar 11. The two bars 10 and 11 and the knock-over comb 14 are assembled on the transverse member 35a.

Various operations which may be performed on the machine illustrated in Fig. 1, and the members by which they are performed, will now be 20 described with reference to Figs. 2 to 22.

Referring first to Figs. 2 to 9, these illustrate several stages in the knitting of the plain or reinforced plated work. 5 is the ground thread, 25 and 6 is the plating thread. The two threads are supplied, respectively, by the rear thread guide 1 and the front thread guide 3. The central thread guide 2 is inactive in this operation, being not supplied with thread, or arrested at the 30 beginning or at the end of the courses. 7 is one of the dividing sinkers and 8 is one of the jack sinkers. The front end of a jack sinker 8 is shown in Fig. 6 and the front end of a dividing sinker is shown in Fig. 7.

35. Referring first to Fig. 6, 9 is the vertical throat of the jack sinker which extends from an upper point 19 to a lower point 20. The upper point 19 is at the lower end of a forwardly inclined edge 18 which extends upwardly as far as the upper edge 8a of the jack sinker. The point 20 is at the upper end of the chin. The dividing sinkers, 40 Fig. 7, are similar to the jack sinkers, with a vertical throat 1d extending from a point 1b at the base of a forwardly inclined edge to a point 1c at the top of the chin. The upper edge of each 45 dividing sinker is stepped down at 7a.

The outlet openings of the thread guides 3, 2, 1 are arranged in the usual manner at a short distance above the stepped-down upper edges 7a 50 (Fig. 7) of the dividing sinkers 7 and at a slightly lower level than the upper edges 8a of the jack sinkers 8 (Fig. 6). 15 is the fabric which is supported by the knock-over comb 14 between whose blades the needles 12 reciprocate.

55. The jack and dividing sinkers, the needles 12, and the knock-over comb 14 cooperate in the usual manner. The only difference relates to the operation of the thread guides. In the present instance, the movements which are performed by a 60 single thread guide, for instance, the rear thread guide 1, in the usual knitting of plain work, are now performed by those thread guides which are supplied with thread, i. e. the front guide 3 and the rear guide 1 in the example illustrated. In 65 other words, those thread guides which are supplied with thread, move together and at the normal velocity imparted to separately operated thread guides in the usual knitting of plain fabrics.

70. The separators 16 of the separator comb will now be described. A separator 16 is allotted to, and placed in line with, each dividing sinker, as best seen in the section, Fig. 8, and a plan view Fig. 9. In this manner, the separators, with 75 their bar 17, form the comb whose length is

equal to that of the row of needles 12. Each separator, as best seen in Fig. 4, has a shank 16a, a reduced end 16b, a parallel upper edge 16c, and a parallel lower edge 16e. A curved portion 16f extending from the upper edge 16c, and a curved 5 portion 16d extending from the lower edge 16e, intersect at 16g and define an upwardly directed projection on the free end of the separator.

Just before the sinking operation, the separator comb moves into the separating position illustrated in Figs. 2 and 3 in which it remains until the sinking operation has been performed, i. e., until the thread guides have moved through one course. In the separating position, the point 16g of each separator is just below the level of the 15 lower ends or outlet openings of the thread guides 3, 2, 1 and between those thread guides which are supplied with thread, i. e. the thread guides 3 and 1. In this manner, the ground thread 5 is separated from the plating thread 6 by the separators without horizontal shifting of the separators. Each advancing jack sinker 8, Fig. 3, engages the plating thread 6 from the front thread guide 3 by the inclined edge 18 which extends upwardly and in forward direction from the upper 25 end 19 of the throat 9. The plaiting thread 6, while moved forward by the inclined edge 18, is separated from the ground thread 5 by the reduced end 16b of the separator, slides down on the inclined edge 18 as the jack sinker advances, and 30 is finally placed on the parallel upper edge 16c of the separator which is at the level of the point 19 at the upper end of the throat 9. The curve 16d which extends from the lower parallel edge 16e of the separator to its point 16g, engages the ground thread 5 and moves it down on the vertical portion of the throat 9 until finally it is at point 20 at the lower end of the throat. Point 20 is the level of the parallel lower edge 16e of the separator. In this manner, the separator, with its shank 16a, holds the plating thread 6 at the point 19 and the ground thread 5 at the point 20 at the upper and lower ends of the throat 9, respectively, by its parallel upper and lower edges 16c and 16e, respectively. The movement of the plating thread 6 toward the point 19, and the movement of the ground thread 5 toward the point 20, of the throat 9 is favored by the fact that both threads extend in downward and forward direction from the respective thread guides 45 50 55 60 65 70 75 80 85 90 95 100 105 110 115 120 125 130 135 140 145 150 155 160 165 170 175 180 185 190 195 200 205 210 215 220 225 230 235 240 ed guides 1, 2 and 3 are now at one or at the other end of a course and are ready to resume their operation as soon as the other members have returned into their initial positions. At this period, the jack and dividing sinkers 7 and 8 move together toward the rear in the direction of arrow A, the needles 12 are raised in the direction of arrow B by their needle bar 13, and the separators 16 advance in the direction of arrow C.

The importance of the reliable separation of the ground and plating threads will now be illustrated by describing some examples.

Fig. 10 shows the use of my separator for the separation of the plating and ground threads 6 and 5, if a third thread 21 is supplied through the thread guide 4 and only the two threads 5 and 6 are to be separated for producing a pattern of some kind, or for varying the texture of the fabric. As in the examples described with reference to Figs. 2 to 9, only those thread guides are operated which are supplied with thread, i. e. the guides 4, 3 and 1.

Fig. 10 shows the separating position illustrated in Fig. 2 in which, as described, the points 16g are between the thread guides 3 and 1. The ground thread 5 is moved to the lower point 20 of the throat 9 in the jack sinkers 8 while the plating thread 6 and the pattern or reinforcing thread 21 are moved to point 19.

Patterns may be knitted with extra plating thread 21' as shown in Fig. 12, by operating the thread guide 2 which was inactive in the examples described, and cutting out the normal plating thread 6 from the thread guide 3, as required by the pattern.

By shifting the separator comb in the direction of the arrow D it is possible to produce patterns in the ground work. The points 16g of the separators 16 are between the outlet openings of the thread guides 2 and 3 and either the thread guide 1 or the thread guide 2 which are supplied with threads of different properties or different colours, are alternatively cut in and out as required by the desired pattern. If the separator comb is still further retracted in the direction D, placing the points 16g between the outlet openings of thread guides 3 and 4, the ground work may be patterned with three threads all having a different colour, or different properties, by cutting in either the thread guide 1, 2 or 3.

In the knitting of backed cloth and in turn-over plating with my separator comb, it is possible to provide particularly simple backing and turn-over sinkers which, notwithstanding their simplicity, are extremely reliable.

In the knitting of work backed with loop plush as shown in Fig. 11, I employ a backing jack sinker 21 whose backing or plush throat is not bordered by a chin in the usual manner but in which a throat 21b extends vertically downwards from point 19 and is connected to point 20 by an incline. On the backing or plush throat, the thread which is sunk by this sinker can be pulled down or slipped off at any desired moment. The thread which has been sunk on the backing throat and is at 19, is prevented from slipping down by the corresponding separator 16. The backing throat is so far in advance of the point 20 that the loop of the backing thread must be longer than the loop of the ground thread. The position of the backing throat 21b and the point 20 is in conformity with the level at which the separators 16 are positioned, the upper parallel edge 16c

of the separator shank 16a being at the level of point 19 while its lower parallel edge 16a is at the level of point 20. The dividing sinkers which cooperate with the backing sinkers 21, are designed like the dividing sinker in Fig. 7, the points 7b and 7c being arranged respectively at the level of the points 19 and 20.

Referring now to Fig. 12 which illustrates the knitting of turn-over work with loop plush backing, jack sinkers 24 are provided which embody a modification of the sinkers 21. They are equipped with the backing or plush throat 21b, like the jack sinkers 21 in Fig. 11, but, in addition with a recess 22b, whose depth is about equal to the thickness of the ground thread 5, at the point 20. The corresponding dividing sinker 25 is without the step at the backing throat 21b, i. e. its throat is vertical from 25a to a recess in the dividing sinker which corresponds to the recess 22b in the jack sinker 24.

With jack and dividing sinkers as illustrated in Fig. 12, the knitting operation is performed with three threads 5, 6 and 21'. The separators 16 are forked, having in addition to the point 16g as described, a second point 29. The second point 29 is positioned at the same level as the point 16g but is set back from it so that it is between the thread guides 3 and 2, when the point 16g is between the thread guides 2 and 1. The separation of the threads is performed with the forked separators in a manner which is analogous to the operation of the plain separators. The third thread 21' from the central thread guide 2 is held by the upper edge of the normal point 16g in downward direction, the same as in the separation of two threads, Figs. 2 to 5, while in upward direction it is held by the lower edge of the second point 29. Consequently, the third or central thread 21' is exclusively guided by the separators 16 which engage it in the notch between the points 16g and 29. The plating thread 6 from the front guide 3 is held by the upper edge of the second point 29 in downward direction, while in upward direction it is held by the inclined edge 18 of the corresponding jack sinker.

Fig. 13 shows the knitting of plated and backed work. The jack sinkers 32 employed for this operation are equipped with a backing or plush throat 32a and a ground-work throat 32b, with an upper point 32c and a lower point 32d, for the plated ground work, Fig. 14. The corresponding dividing sinkers 32' are without a backing or plush throat but only have a vertical throat 33c with an upper point 33a and a lower point 33b, Fig. 15.

It will be understood from the foregoing description that with a machine having the separator comb according to my invention, it is possible to operate with two or three threads on flat knitting machines having any desired needle division, at the same velocity at which the old machines were operated with a single thread only. In other words, the normal velocity of operation for plain work is practicable in plating, reinforcing, simple backing, backing of plated or reinforced work, in turn-over plating or coloured patterning and—which is novel—in the backing of plated reinforced or turn-over work, i. e. coloured-pattern work. All these operations can be performed because the threads are reliably separated by the separator comb and therefore it is possible to select the most favorable lead of the thread guide in front of that jack sinker which is performing its function at a given time.

In order to move the separator comb out of the way altogether, for instance, if needles 12 or sinkers are to be exchanged, or the beginning comb (not shown) is to be inserted, I may provide a handle, or handles, 56, Fig. 1, on the oscillating shaft 48, with a pin 56a on an arm of the handle, or each handle, which is adapted to be engaged by a catch 57. The catch 57 is fulcrumed at 58 in a block 59 on the bracket 47 and serves for holding the separator comb after it has been moved out of the way.

I wish it to be understood that I do not desire to be limited to the exact details of construction shown and described for obvious modifications will occur to a person skilled in the art.

I claim:

1. In a flat knitting machine, a set of frame needles, a set of jack sinkers each having a notch including a vertical backing throat and a ground-work throat below and at the rear of said backing throat, a set of dividing sinkers, each having a notch including a vertical throat whose height is equal to the added heights of the two throats in said jack sinkers, a separator comb adapted to cooperate with said sinkers, a thread separator per dividing sinker on said comb, at least one upwardly curved point at the free end of each separator, an upper parallel edge, and a lower parallel edge on each separator, the vertical distance between said edges being equal to the height of the throat in said dividing sinkers.

2. In a flat knitting machine, a set of frame

needles, a set of jack sinkers, a set of dividing sinkers, thread guides, a separator comb having a thread separator per dividing sinker, an upwardly directed projection on the free end of each separator for cooperation with said thread guides, and means for displacing said comb with respect to said sinkers and thread guides.

3. In a flat knitting machine, a set of frame needles, a set of jack sinkers, a set of dividing sinkers, thread guides, a separator comb having a thread separator per dividing sinker, a pair of upwardly directed projections on the free end of each separator for cooperation with said thread guides, and means for displacing said comb with respect to said sinkers and thread guides.

4. In a flat knitting machine, a set of frame needles, a set of jack sinkers each having a throat, a vertical edge in the throat of each jack sinker, a set of dividing sinkers each having a throat, a vertical edge in the throat of each dividing sinker whose height is equal to that of the said vertical edge in the throat of each jack sinker, a separator comb adapted to cooperate with said sinkers, a thread separator per dividing sinker on said comb, at least one upwardly directed projection on the free end of each separator for cooperation with said thread guides, an upper parallel edge, and a lower parallel edge on each separator, the vertical distance between said edges being equal to the height of said vertical edges.

MAX NEBEL.
